ROBERT S. RILEY, OF WORCESTER, MASSACHUSETTS, ASSIGNOR TO SANFORD RILEY STOKER COMPANY, OF WORCESTER, MASSACHUSETTS, A CORPORATION OF MASSACHUSETTS.

PULVERIZING MILL.

Application filed January 3, 1924. Serial No. 684,231.

This invention relates to a mill for pulverizing dry coal, cement or other material of similar structure. This mill is designed for continuous operation, with automatic 5 feed of the coarse material to one end of the mill and continuous delivery of the pulverized product from the other end of the mill.

One object of my invention relates to the provision of improved devices for producing 10 the pulverizing action and particularly to an improved construction of roll hammer for use in such a machine, this hammer having both a roller and a ball action. I have also provided an indicating device by means of 15 which the position of the roll hammers relative to the tread or bull ring may be observed during the operation of the machine.

A very important feature of the invention lies in the particular construction of the bull 20 ring, the conical converging walls of which are effective to feed the material under the hammers and thus enable the machine to operate without the use of the customary plows, saving much power and expense.

25 Another object of my invention is to provide an improved mechanical separating device at the discharge end of the mill by means of which the coarser particles of material may be separated from the fine pulverized 30 particles and may be returned to the mill for further reduction.

Another feature of my invention relates to the provision of an improved separator of the gravity type which will return any remaining coarse particles or tailings to the 35 hopper from which the machine is fed. In the preferred form, the operation of this gravity separator may be adjusted and controlled by regulating devices to be described.

40 I have also provided an improved form of hopper, having provision for adjustment of the feed without change in the rate of actuation thereof.

In a modified form of my invention, I have 45 shown a machine in which a supplemental pulverizing agency is provided, acting upon the material after it has passed through the roll hammer mechanism and serving as a substitute for the mechanical separating device 50 above referred to.

My invention further relates to arrangements and combinations of parts which will be hereinafter described and more particularly pointed out in the appended claims,

A preferred form of the invention is shown 55 in the drawings in which

Fig. 1 is a longitudinal sectional elevation of my improved machine;

Fig. 2 is an end elevation thereof, looking 60 in the direction of the arrow 2 in Fig. 1;

Fig. 3 is a sectional elevation of one of the roll hammers and its support;

Fig. 4 is a transverse sectional elevation, taken along the line 4-4 in Fig. 3 and showing the spider or support for the ball hammers;

Fig. 5 is a perspective view of the mechanical separating device;

Fig. 6 is a diagrammatic plan view of certain driving connections;

Fig. 7 is a sectional end elevation of the hopper and feeding device;

Fig. 8 is a partial longitudinal sectional elevation of the same parts;

Fig. 9 is a detail plan view of the hopper 75 adjusting mechanism; and

Fig. 10 is a partial sectional side elevation showing a modified construction.

Referring particularly to Figs. 1 and 2, I have shown a pulverizing mill comprising 80 a casing 10 within which is rotatably mounted an annular rotatable member 11 having a gear 12 formed on its outer face. The member 11 rotates in fixed bearings 13 and acts as a support for a bull ring 14. The ring 14 85 and member 11 have co-operating tapered contact surfaces and the ring 14 is securely held to its seat in the member 11 by a head 16 bolted to the side of the member 11 and having clamping screws 17 threaded therein 90 and engaging the larger end of the bull ring 14.

A plurality of roll hammers 20 are rotatably mounted upon arms 21 (Fig. 3) which in turn are pivoted at 24 to a frame or spider 95 25 keyed or otherwise secured to a drive shaft 26. The frame 25 is provided with pairs of spaced arms or projections forming separated bearings for the arms 21, as clearly indicated in Fig. 4. Upon the face adjacent the 100 rolls, the frame 25 is provided with inclined ribs 27 which strengthen the bearing arms and act to assist the feed of material.

Each roll 20 has an end ring 30 secured thereto by screws or bolts 31 and providing 105 an annular recess for a collar 32 fixed to its arm 21 by a tapered pin 33. Each roll 20 is also preferably provided with a bushing

or bearing sleeve 34 and suitable provision is made for introducing lubricant to the bearing through an oil passage 35 in the arm 21. A shield 36 excludes coal or other material from the bearings of the arms 21.

An indicator arm 37 is fixed to one of the roll hammer arms 21 and extends toward the axis of the shaft 26. A rod 38 is slidable in a groove 39 in the shaft 26 and extends beyond the right hand end of the shaft, as shown in Fig. 1. A pointer 40 may be provided on the casing 10^a of the driving mechanism and the end of the rod 38 may be graduated as indicated at 41. A glance at these graduations will indicate accurately the position of the roll hammers with reference to the bull ring at any time during the operation of the machine.

The axis of the drive shaft 26 is preferably offset downwardly from the axis of the member 11 and gear 12, for a purpose to be described.

Any suitable driving means may be provided for rotating the ring supporting member 11 and the roll hammer supporting frame 25. As shown herein, the shaft 26 is provided with a gear 42 (Figs. 1 and 6) engaged by pinion 43 mounted on a counter shaft 44 having a pinion 45 meshing with a gear 46. The gear 46 is fixed to a second counter shaft 47 having a pinion 48 which drives the ring gear 12 previously described. Shaft 44 may be driven by an electric motor or in any other convenient manner.

A hopper 50 (Figs. 1 and 7) is provided for feeding the coarse material to the pulverizing mill. The hopper may be connected by a pipe 51 to any suitable storage space from which a supply of raw material may be conveniently received. The hopper 50 has an offset discharge opening 52 (Fig. 7) and has a feeding device 53 rotatably mounted between the hopper 50 and the discharge opening 52. The feeding device 53 is mounted upon a shaft 54 to the end of which is secured a ratchet ring or cog wheel 56 with which a pawl 57 is intermittently engaged. The pawl 57 is mounted upon a feed lever 58 (Fig. 2) connected by a link 59 to a pin 60 eccentrically mounted in a gear 61 engaged and driven by a pinion 62 on the shaft 26.

Through these connections, the feeding device 53 in the hopper 50 is angularly advanced with a relatively slow intermittent movement. The feeding device 53 has a plurality of axial feeding blades 63 (Fig. 7). As the blades 63 rotate past an opening 64 in the side of the hopper 50, the recesses between the blades are filled with coal or other material, which is carried around by the blades and is discharged through the opening 52.

It is often desirable to change the rate of feed of material to the mill without changing the gear connections to the crank gear 61 and for this purpose I have provided the

feed adjusting device shown in detail in Figs. 7, 8 and 9. This adjusting device comprises a sleeve 65 slidable axially of the shaft 54 and having a series of sector-shaped projecting members 66 at one end thereof. One of the members 66 extends between each two adjacent blades 63 of the feeding device 53. These members 66 are closed at their outer or segmental faces, so that they complete a desired portion of the cylindrical surface of the feeding device and leave no recess in such portion to receive material as the blades 63 rotate past the opening 64. Suitable means is provided for adjusting the sleeve 65 and the adjusting member 66 axially of the shaft 54, such means comprising wing nuts 67 (Fig. 9) threaded on rods 68 fixed in the hopper casing 50. The nuts 67 are grooved or flanged and fit between the upper and lower parts of a plate 69 which acts as a yoke for a grooved end portion 70 of the sleeve 65. By turning the nuts 67 the sleeve 65 and members 66 may be adjusted axially.

With this construction, the length of the recesses in the feeding device may be varied to increase or decrease the capacity of the feeding device at each intermittent actuation thereof.

A blade 72 (Fig. 7) is secured in the hopper 50 and tends to break up adhering masses of coal as they enter the hopper and to cause pieces of iron or other heavy material to fall to a recess or pocket 73 formed below the feeding opening 64 and well adapted to receive such heavy material. A cap or plate 74 closes an opening 75 through which the material collected in the pocket 73 may be removed.

The material fed from the hopper passes downward in the casing 10 and is gradually fed to the bull ring past the spider 25. The hammers 20 have a combined roller and ball action on the material. The straight line or conical part of the hammer is preferably at a slight angle to the adjacent surface of the bull ring, so that the coal is subject to an increasing crushing action as it is advanced across the ring. The rounded or ball portion of the hammer then has a pulverizing action similar to the usual ball mill.

As the coal or other material is ground or pulverized between the balls 20 and the bull ring 14, the fine pulverized material is drawn through a discharge opening 75 in the casing 10 into a gravity separator 76 with which is connected a suitable exhaust fan (not shown).

As the material is drawn toward the discharge opening, it passes a fan-like mechanical separator or rejector 80, most clearly shown in Fig. 5. The rejector 80 comprises a series of four blades 81 arranged axially of the driving shaft 26 and extending radially from the axis. Upon the leading face of each of the blades 81 there is provided a guide or

flange 83 which is inclined toward the axis of the shaft 82 in the direction of the discharge opening 75.

As the pulverized material passes through the fan-like rejector 80, the fine material passes freely along into the gravity separator 76 but the heavier particles are engaged by the blades 81 and are restrained from outward movement by the flanges 83. As each blade and flange approaches the lowest point in its circuit, the collected material falls backward into the bull ring 14 and is again acted upon by the roll hammers 20.

The fine material continues its upward course through the gravity separator 76 which has an outer casing 85 and an inner conduit 86 having an extension 87 communicating with the hopper 50. A swinging check valve 88 permits downward movement of material through the extension 87 but prevents entrance of air in the opposite direction.

A discharge pipe 90 at the top of the casing 85 is connected to suitable exhaust mechanism (not shown) as previously stated. The pipe 90 has a sleeve 91 slidably mounted thereon, with its lower end extending below the upper end of the conduit 86. Adjusting screws 92 are provided by which the sleeve 91 may be raised or lowered to vary the projection of the sleeve into the conduit 86.

As the pulverized material is drawn upward through the gravity separator 76, it necessarily follows the direction of the arrows *a* in Fig. 1, passing over the upper end of the conduit and downward around the lower end of the sleeve 91. As the direction of movement is reversed, the heavier particles fall into the conduit 86 and are delivered by gravity to the hopper 50, while the lighter particles pass upward to the discharge pipe 90.

Suitable packing rings 95 and 96 (Fig. 1) are provided to prevent escape of the pulverized material during its passage through the mill. An annular pocket 97 is formed at the right hand end of the bull ring 14, within which articles of iron and other heavy material may conveniently collect. A ring or flange 98 on the shaft 26 forms an inner limit or stop for the hammers 20.

The inner face of the bull ring 14 is formed with two oppositely inclined or conical surfaces and the effect of these oppositely inclined surfaces is very important. The action of the conical or inclined surface on the entrance side, assisted by centrifugal force, is to feed the material forward under the roll hammers, while the action of the second inclined surface is to reverse the feed of the coarser particles, returning them under the hammers, while the finer material passes along to the rejector 80.

In Fig. 10, I have shown a slightly modified form of my invention in which a combined pulverizing and rejecting device is provided between the bull ring 14 and the lower end of

the gravity separator 76. This device comprises a disc 100 mounted upon an independently rotated shaft 101 and having a series of pins 102 fixed in the left hand face thereof, alternating with pins 103 fixed in a casing member 104.

As the pulverized material leaves the hammers, it is drawn around the outer edge of the disc 100 as indicated by the arrow *b* in Fig. 10 and is then drawn inward past the pins 102 and 103 to the discharge opening 105 at which point it is delivered to the gravity separator 76. The disc 100 is rotated at a speed much faster than that of the roll hammers or bull ring and a considerable additional pulverizing effect is achieved by passing the material between the series of pins 102 and 103. The heavier particles are struck and thrown outward by the pins 102 and strike an inclined inner wall of the casing member 104, rebounding therefrom under the hammers 20 for further pulverizing action.

Having thus described my invention, it is believed that the operation will be clearly apparent. A supply of suitable material is fed to the hopper 50 through the feed pipe 51 or in any other convenient manner and the material is intermittently fed from the hopper in measured quantities to the roll hammers and bull ring which are preferably rotated as described in opposite directions. The rolls 20 are free to turn upon their supporting pins and in contact with the bull ring and are swung strongly outward by centrifugal force.

The outer wall of the roll portion of each hammer is inclined relatively to the adjacent conical wall of the bull ring, so that the material as it advances is subject to an increasing crushing action, but the roll wall and ring are out of direct contact in this portion of the mechanism. The material is fed forward by the combined effect of centrifugal force and the outwardly inclined tread of the bull ring. The return of the coarser particles under the hammers has been already explained.

As the material is pulverized, it first passes the rejector 80 which turns back the coarser particles for further treatment. The finer particles pass to the gravity separator 76 where further separation by gravity takes place. The coarse particles or tailings separated at this point are returned to the hopper for further reduction.

The combined crushing and pulverizing action of the hammers 20 has been fully described. By offsetting the axis of rotation of the spider and hammers relatively to the bull ring or tread 14, the effect of gravity on the hammers is substantially balanced by the increased centrifugal action at the longer radius and the pressure of the hammers on the material is largely equalized.

Having thus described my invention and the advantages thereof, I do not wish to be limited to the details herein disclosed other-

wise than as set forth in the claims, but what I claim is:—

1. A pulverizing mill having, in combination, a bull ring, means to positively rotate said ring, a rotatable member, a plurality of roll hammers each individually rotatable and pivotally connected to said member, and means to positively rotate said member, said hammers having ball shaped outer ends and straight line portions associated therewith, the ring and member being driven continuously in opposite directions. 5
2. A pulverizing mill having, in combination, a bull ring, means to positively rotate said ring, a rotatable member, a plurality of roll hammers rotatably and pivotally connected to said member, and means to positively rotate said member, said hammers having ball shaped outer ends and having straight line roll surfaces slightly inclined to the adjacent inner face of the bull ring when swung outward to approximate engagement therewith, the ring and member being driven continuously in opposite directions. 10
3. A pulverizing mill having, in combination, a bull ring, means to positively rotate said ring, a rotatable member, a plurality of roll hammers rotatably and pivotally connected to said member, and means to positively rotate said member, said hammers having ball shaped ends and straight line roller surfaces slightly inclined to said bull ring, whereby to crush and pulverize the material with an increasing crushing roller action at the entrance side of the ring and with a ball pulverizing action at the discharge side of the ring. 15
4. In a pulverizing mill, a rotating member, swinging arms mounted thereon, rotatable crushing devices on said arms, and means to indicate the radial position of said devices. 20
5. In a pulverizing mill, a rotating member, swinging arms mounted thereon, rotatable crushing devices on said arms, a shaft on which said member is mounted, an indicating rod slideable axially of said shaft, and connections from said rod to said swinging arms. 25
6. In a pulverizing mill, a bull ring, and means to positively rotate said ring, a rotatable member, a plurality of roll hammers each individually rotatable and pivotally mounted to swing on said member, and means to rotate said member, the axis of rotation of said member being out of alignment with the axis of said ring. 30
7. In a pulverizing mill, a bull ring, and means to positively rotate said ring, a rotatable member, a plurality of roll hammers each individually rotatable and pivotally mounted to swing on said member, and means to rotate said member, the axis of rotation of said member being positioned slightly below the axis of said ring. 35
8. A pulverizing mill having, in combination, a bull ring, means to positively rotate said ring, a rotatable member, a plurality of roll hammers each individually rotatable and pivotally connected to said member, and means to positively rotate said member, said hammers having ball shaped ends and straight line roller surfaces slightly inclined to said bull ring, whereby to crush and pulverize the material with an increasing crushing roller action at the entrance side of the ring and with a ball pulverizing action at the discharge side of the ring, the bull ring being always out of direct contact with the hammers in the roller portions thereof. 40
9. A pulverizing mill having, in combination, a bull ring, means to positively rotate said ring, a rotatable member, a plurality of hammers mounted thereon for substantially radial operative movement, and means to rotate said member, said bull ring having a conical surface co-operating with centrifugal force to advance the material toward the central portion of the tread, the bull ring and member being driven continuously in opposite directions. 45
10. A pulverizing mill having, in combination, a bull ring, means to positively rotate said ring, a rotatable member, a plurality of cone shaped hammers mounted thereon for substantially radial operative movement, and a rotor to rotate said member, said bull ring having a conical surface co-operating with centrifugal force to return coarser particles from the crushed material toward the central portion of the tread, the cone portion of the hammers and the ring being angularly spaced from each other. 50
11. A pulverizing mill having, in combination, a bull ring, means to positively rotate said ring, a rotatable member, a plurality of cone shaped hammers mounted thereon for substantially radial operative movement, and means to rotate said member, said bull ring having oppositely disposed conical surfaces co-operating with centrifugal force to feed the material toward the central portion of the tread, the cone portion of the hammers and the ring being angularly spaced from each other. 55
12. A pulverizing mill comprising a bull ring, a rotating member, a plurality of roll hammers movably mounted on said member, and means to positively rotate said ring and said member, said hammers each comprising a ball shaped end and a straight side roll portion, the roll portion of said hammers being positioned at a slight angle to the adjacent tread of said ring, and thus providing a crushing space having converging and relatively movable walls out of direct contact with each other throughout the greater portion of their length when in crushing relation. 60
13. A pulverizing apparatus comprising a casing having an inlet for coarse material and an outlet for the finely pulverized ma- 65

- terial, a bull ring and rolls associated therewith near the inlet for pulverizing the coarse particles, and rapidly revoluble impact members arranged in the path of the material traveling from the first zone to the outlet which are arranged to finely pulverize the material fed thereto.
14. A pulverizing apparatus comprising a casing provided with an inlet and an outlet respectively on opposite sides thereof, means forming two pulverizing zones connected by an annular passage, means in the first zone adjacent to the inlet for crushing the coarse material preliminarily, and means in the second zone adjacent to the outlet arranged to pulverize the material finely which is fed thereto and to return the coarse particles to the first pulverizing zone.
15. A pulverizing apparatus comprising a casing having an inlet and centrally located outlet on opposite sides thereof, means forming two chambers in said casing, a bull ring and rolls in the inlet chamber arranged to crush the material preliminarily, and impact members in the second chamber arranged to finely pulverize the material as it passes to the outlet.
16. A pulverizing apparatus comprising a casing having an inlet and a centrally located outlet on opposite sides thereof, means forming two pulverizing zones connected by an annular passage, means including yieldable, pivotally mounted crushing members arranged in the first zone adjacent to the inlet for preliminarily crushing the material, and revoluble impact members on the rotor and stationary impact members which are located on the casing in the second zone near the outlet and serve to finely pulverize the material as it travels inwardly towards the outlet.
17. A pulverizing apparatus comprising a casing having an inlet and a centrally located outlet on opposite sides thereof, means forming two pulverizing zones connected by an annular passage, means including yieldable, pivotally mounted revoluble members in the first zone adjacent to the inlet to pulverize the material preliminarily, a series of pegs in the second zone revoluble about the axis of the pulverizing members in the first zone and stationary pegs on the casing associated with the revoluble pegs to pulverize the material finely as it passes inwardly towards the outlet.
18. A pulverizing apparatus comprising a casing having an inlet and a centrally located outlet on opposite sides thereof, means forming two pulverizing zones between the inlet and outlet which are connected by an unobstructed annular passage, means including yielding, pivotally mounted revoluble members in the first zone near the inlet to pulverize the material preliminarily, and impact members in the second zone between said passage and the outlet which revolve rapidly about a horizontal axis and pulverize the material finely as it passes inwardly towards the outlet.
19. In a pulverizing mill having a pulverizing mechanism, a hopper, a feeding connection from said hopper to said mechanism, and a discharge conduit, the combination therewith of a mechanical separator in the entrance to said conduit, a gravity separating device located in said conduit and a means to collect in said gravity separating device the coarse tailings which pass said mechanical separator and to return said tailings to said hopper.
20. In a pulverizing mill having a casing with a discharge opening, a pulverizing mechanism including a plurality of rotatable crushing devices, and a bull ring cooperating with said rotatable devices, the combination therewith of a disk rotatable relative to said ring and adjacent said opening, a plurality of pins arranged in concentric circles on said disk, and additional pins fixed on said casing and alternating with said circles of movable pins, said pins and disk acting upon the material after it has passed between the rotatable crushing devices and the bull ring and acting to further pulverize said material.
21. A pulverizing apparatus comprising a casing having an inlet for coarse material and an outlet for pulverized material, means forming two pulverizing zones adjacent the inlet and outlet respectively, revoluble members in the first zone arranged to preliminarily crush coarse material, impact members in the second zone for producing fine pulverization, means for driving the impact members, and means for driving the revoluble members at a different speed from that of the impact members.
- In testimony whereof I have hereunto affixed my signature.
- ROBERT S. RILEY.
